[57] CLAIM

The ornamental design for a golf practice putting cup storable in a compact disc box, as shown.

DESCRIPTION

FIG. 1 is a top perspective view of the preferred embodiment of a golf practice putting cup storable in a compact disc box showing my new design;

FIG. 2 is a front elevational view thereof, the device being circular, the sides and front and rear view are all a mirror image view thereof;

FIG. 3 is a top plan view thereof; and,

FIG. 4 is a bottom plan view thereof.
